UNITED STATES PATENT OFFICE

CHARLES A. HUFFMAN, OF LONGVIEW, WASHINGTON, ASSIGNOR OF ONE-HALF TO
THE LONG-BELL LUMBER COMPANY, OF KANSAS CITY, MISSOURI, A CORPORATION
OF MISSOURI

YIELDING ANVIL-KNIFE DOOR FOR GRINDING OR MASTICATING HOGS

Application filed June 4, 1928. Serial No. 282,667.

This invention relates to grinding or masticating hogs utilizing a double disk or V-shaped grinding wheel cooperating with a pair of fixed anvil knives so arranged as to conform to the faces of the rotating disk, and has for its object to provide a yielding anvil knife door or carrier held by breakable members, whereby the carrier may swing back from the rotating disk a predetermined distance to permit a piece of metal or relatively hard foreign material to pass through the machine. In other words the invention has for its object to provide a simple and efficient safety device for the protection of the hog or masticator in case undue resistance between the rotary and fixed knives should be encountered.

With the construction of the invention, the anvil knife door or carrier may yield or swing away from the rotating disk sufficiently far to permit a piece of material of maximum size, such as for example 12" x 12" x 30" to pass through the machine without injury thereto or to the driving mechanism thereof.

Another object of the invention is to provide strong, durable, efficient and inexpensive protection means of the type outlined whereby the use of friction clutches or the like for the protection of the machine are entirely obviated; and in order that it may be fully understood, reference is to be had to the accompanying drawings, in which:

Figure 1 is a side elevation of a hog embodying the invention.

Figure 2 is an end view partly broken away to disclose parts otherwise hidden.

Figure 3 is an enlarged central vertical section through the movable knife of the invention.

Figure 4 is a detail perspective view of the anvil knife carrier or door as viewed from the cutting face thereof.

In the said drawings where like reference characters identify corresponding parts in all of the figures, 1 indicates each of a pair of sectional webbed side frames constituting a support and housing on which is journaled a shaft 2 driven by a pulley 3, or by any other suitable power. The shaft 2 is driven in the direction of the arrow, Figure 3, and carries a disk 4 of V-shape in cross section

equipped with a plurality of cutter knives 5 adjustable toward and from the faces of the disk to regulate the coarseness of the cut. To centralize the rotating disk, a pair of adjusting bolts 6 are carried by the side frames with their ends in position to contact with the edges of the disk so that the shaft and disk may be adjusted or centered between the frames.

Vertically above the cutting disk, the frame and casing are so formed as to provide a filling chute or opening 7. The frame 1 to one side of the shaft 2 in the direction of rotation of said shaft, is extended upwardly, and journaled in bearings 8 carried by the upper end thereof is a yielding anvil knife shaft 9 on which is keyed or otherwise secured a V-shaped knife carrier or door 10 equipped with a pair of cutting knives 11 along its side edges in close proximity to the rotating disk. The rotating disk knives and the fixed anvil knives thus cooperate together in the grinding of material fed to the machine.

Upon consideration of Figure 3, it will be noted that the natural tendency of the fixed V-shaped carrier or door 10 is to swing away from the rotating disk 4. In order to hold said carrier in advanced or operative position, the shaft 9 projects beyond the frames 1, and keyed to the ends of said shafts are a pair of downwardly and outwardly inclined arms 12 in abutment with outwardly projecting stop lugs or studs 13 cast or otherwise secured to the frames 1. To maintain the arms 12 against the studs 13 so that the knives shall be properly spaced and to permit the whole assembly to swing to the dotted line position shown in Figure 1, should strain above a predetermined maximum be placed on the machine, the ends of the arms are held in clamped position against the studs by breakable plates 14 bolted or otherwise replaceably secured to the frames 1, as illustrated. The plates 14 are adapted to withstand a predetermined strain by being formed with a transverse groove or kerf forming a breaking point or line 15.

It will be evident from the above description that the strength of the break-plates

will determine the maximum strain to which the parts of the machine may be placed. If a strain greater than predetermined by the plates is imposed on the fixed knives and carrier, the plates will break and the fixed anvil knife carrier or door will move away from the rotating disk to permit foreign material to pass by without injury to the machine.

- 10 In the machine as illustrated, the anvil knife carrier is housed by means of a plate 16 bolted to the inclined portion of the frames 1, but it will be evident that if desired the pivoted carrier may be formed integrally 15 with a suitable housing or protecting plate so that the entire assembly and housing may swing away from the machine upon the breaking of the safety plates, as will be readily understood. The lower corners of the plates 20 16 are recessed as at 17 to accommodate the break-plates 14 which preferably should fit flatwise against the frames 1, as shown. It will also be evident that if desired, springs or other shock absorbing devices may be applied to the arms 12 to prevent the knife carrier 10 from swinging out with such force 25 as to fracture or injure the cover plate 16 of the mechanism.

From the above description, it will be apparent that I have produced a machine of the character described which possesses all of the features of advantage set forth as desirable, and while I have described and claimed the preferred embodiment, it is to be understood 35 that I reserve the right to make all changes properly falling within the spirit and scope of the appended claims.

I claim:

1. In a masticating or grinding hog, a rotating V-shaped cutter, a second cutter of V-shape intermeshing with said rotating cutter, a shaft carrying said second cutter, and means co-operating with said shaft to prevent movement of the second cutter away 45 from the rotating cutter.

2. In a masticating or grinding hog, a rotating V-shaped cutter, a second cutter of V-shape intermeshing with said rotating cutter, a shaft carrying said second cutter, and breakable means cooperating with said shaft to prevent movement of the second cutter away from the rotating cutter.

3. In a masticating or grinding hog, a rotating cutter of V-shape, a second cutter of V-shape intermeshing with said rotating cutter, a shaft carrying said second cutter, and arms secured to said shaft to prevent movement of the second cutter away from 60 the rotating cutter.

4. In a masticating or grinding hog, a suitable frame, a rotating V-shaped cutter therein, an oscillatory cutter of V-shape intermeshing with said rotating cutter, means for limiting the movement of the oscillating cut-

ter in one direction, and breakable means preventing movement of the oscillating cutter in the other direction.

5. In a masticating or grinding hog, a suitable frame, a rotating V-shaped cutter therein, a shaft journaled on and extending transversely of said frame, a second cutter of V-shape carried by said shaft and intermeshing with the rotating cutter, arms secured to said shaft, and breakable lugs in contact with said arms to prevent movement of the second cutter away from said first cutter.

6. In a masticating or grinding hog, a suitable frame, a rotating V-shaped cutter therein, a shaft journaled on and extending transversely of said frame, a second cutter of V-shape carried by said shaft and intermeshing with the rotating cutter, means for preventing the second cutter from moving in one direction, and breakable lugs to prevent movement of the second cutter in the opposite site direction.

7. In a masticating or grinding hog, a suitable frame, a rotating cutter therein, a shaft journaled on and extending transversely of the frame, a second cutter carried by said shaft for cooperating with the rotating cutter, arms carried by said shaft, stop lugs on the frame for contacting with said arms for preventing movement of the second cutter in one direction, and breakable plates cooperating with the arms in preventing movement of said cutter in the opposite direction.

8. In a masticating or grinding hog, a suitable frame, a rotating cutter therein, a shaft journaled on and extending transversely of the frame and projecting beyond the sides thereof, a second cutter carried by said shaft for cooperating with the rotating cutter, a pair of arms extending from the projecting ends of said shaft, a stop lug for contacting with the arms to prevent movement thereof in one direction, and breakable plates carried by the frames for preventing movement of the arms in the opposite direction.

9. In a masticating or grinding hog, a rotating cutter of V-shape, a second cutter of V-shape intermeshing with the said first-named cutter and pivotally mounted in a plane above its line of cooperation with said rotating cutter, and means for normally maintaining the fixed cutter in position for co-operation with the rotating cutter.

10. In a masticating or grinding hog, a rotating cutter of V-shape, a second V-shaped cutter intermeshing with said rotating cutter and pivotally mounted in a plane above its line of enmeshment with the rotating cutter and yielding means for normally maintaining the fixed cutter in position for cooperation with the rotating cutter.

11. In a masticating or grinding hog, a rotating V-shaped cutter, a second V-shaped cutter enmeshed with said rotating cutter and
